UNITED STATES PATENT OFFICE.

EDMOND LEVEILLE, OF SALEM, MASSACHUSETTS.

CONNECTION FOR RAIL-JOINTS.

1,147,251.

Specification of Letters Patent. Patented July 20, 1915.

Application filed May 31, 1913. Serial No. 771,103.

To all whom it may concern:

Be it known that I, EDMOND LEVEILLE, a citizen of the United States of America, and a resident of Salem, in the County of Essex and State of Massachusetts, have invented 5 certain new and useful Improvements in Connections for Rail-Joints, of which the following is a specification.

This invention relates to devices for connecting the abutting ends of car rails, the object being to provide a means for effectually preventing the breaking down of the joint by the constant hammering thereon of the wheels of passing trains.

10 The invention consists of certain novel features of construction and arrangement of parts which will be readily understood by reference to the description of the drawings and to the claims hereinafter given.

15 Of the drawings, Figure 1 represents a plan of a device embodying the features of the present invention applied to two abutting rails. Fig. 2 represents an elevation of the same, and Fig. 3 represents a vertical 20 section of the same, the cutting plane being on line 3—3 on Fig. 1.

Similar characters designate like parts throughout the drawings.

In the drawings, 10—10 are two rails the 25 ends of which abut at 11. Adjacent to the end of each rail a portion of the tread surface is cut away as indicated at 12 forming recesses therein. At the ends of each rail the web 13 has projecting from one face 30 thereof beneath the recesses 12 a rib 14 the upper and lower walls of which are inclined as indicated in Figs. 2 and 3. Opposite this ribbed face of the web 13 is positioned a side member 15 fitting the depression in that 35 side of the rail 10, this side member 15 having formed integral therewith a bottom plate 16 on which the flanged bottom 17 of the rail 12 rests. The side member 15 is provided 40 with a groove 18 extending longitudinally thereof, the upper and lower side walls of which are inclined and adapted to fit over the inclined walls of the projecting rib 14 formed integral with the web 13 of the rail 10. The web 13 is provided with a plurality 45 of longitudinal slots 19 through each of which extends a bolt 20, this bolt being provided with the squared portion 21 fitted to an opening through the side member 15.

50 The opposite end of each bolt 20 is threaded and extends through the side member 22 fitted to the depression on the opposite side

of each rail 10 between the upper and lower flanges thereof. A nut 23 is threaded to the end of each bolt 20 and locks the side members 15 and 22 firmly together between the 55 upper and lower flanges of the rail 10. It is obvious that by turning the nuts 23 the side member 15 may be drawn toward the web 13 and more firmly locked upon the wedge-shaped projection 14 thereof. The side 60 members 15 and 22 extend from one rail 10 to the other rail 10, making a rigid connection between the same, thereby keeping the two rails in perfect alinement at all times. This member 15 has an upward extension 65 24 fitting the recesses 12, the upper surface of this extension conforming to the tread surface of the rails 10. As the trains pass over the rails 10 the wheels are prevented by this 70 upward extension 24 from hammering the joint, wearing down the head, and loosening the connections between the rails. The bottom plate 16 rests upon cross ties 26 and is secured thereto by means of the spikes 27 and 28. The spikes 27 are positioned in 75 notches 29 formed in the outwardly extending flange of the member 15. The spikes 28 are positioned in notches 30 in the edge of the outwardly extending flange of the member 22 and extend through openings 80 31 formed in the bottom plate 16. By means of these spikes 27 and 28 which bear upon the upper surfaces of the outwardly extending flanges of the members 15 and 22 all of the connecting members are rigidly secured 85 together and to the ties 26, the lower faces of the abutting ends of the rail 10 being held firmly against the bottom plate 16, while said bottom plate is securely positioned upon 90 said ties. By means of this construction the 95 abutting ends of the rails are held securely locked together and retained in alinement at all times by means of alined projections 14 positioned in the grooves of the member 15, thereby retaining the tread surface of the rail 100 in the same plane with the upper face of the extension 24 under all conditions. The fact that the bottoms of the abutting rails rest upon a bottom plate formed integral with the side member 15 and extending 105 from one rail to the other assists in accomplishing this same result.

It is believed that the operation and many advantages of the invention will be fully understood from the foregoing description.

Having thus described my invention, I claim:

In a device of the class described, the combination with two abutting rails having on one side thereof aligned ribs tapering outwardly and recesses in the abutting heads; of a side member for said rails having a vertical extension fitting said recesses, a longitudinal groove, with inclined walls, to receive said ribs, an outwardly extending flange and a horizontal plate extending from the outer edge of said flange and adapted to support said rails; a side member for the opposite sides of said rails provided at its lower edge with an outwardly extending flange and having the upper and lower edges inclined to conform with the inner faces of the upper and lower flanges of said rails; bolts extending through elongated slots in

the webs of said rails for locking said side members together and forcing the upper and lower inclined edges into contact with the inclined inner faces of the upper and lower flanges of said rails; two sets of members for securing the rails to a cross tie, each set being provided with heads engaging the outwardly extending flange of one of said side members; and means for positioning said members.

Signed by me at 4 Post Office Sq., Boston, Mass., this 26th day of May, 1913.

EDMOND LEVEILLE.
